UNITED STATES PATENT OFFICE.

CYRUS H. KLINGER AND JAMES J. REYNOLDS, OF PHILADELPHIA, PENNSYLVANIA, ASSIGNORS TO SIEGMUND PRINCE, OF PHILADELPHIA, PENNSYLVANIA.

MACHINE FOR PRESSING HATS.

SPECIFICATION forming part of Letters Patent No. 694,756, dated March 4, 1902.

Application filed September 3, 1901. Serial No. 74,071. (No model.)

To all whom it may concern:

Be it known that we, CYRUS H. KLINGER and JAMES J. REYNOLDS, citizens of the United States, and residents of Philadelphia, in the county of Philadelphia and State of Pennsylvania, have invented a new and useful Machine for Pressing Hats, of which the following is a specification.

The object of our invention is to provide improved means for holding the material to be operated upon during the operation of pressing and shaping in such manner as to permit of a sufficient yielding or giving of the material to form the shape required. In this way we dispense with the necessity of having the material held and stretched by the hands of operators during the process of pressing and shaping, as is the present practice.

Our apparatus comprises three elements, one recessed for the crown, with marginal surface for the rim, one provided with a crown projection corresponding with the recess of the first element and having a surrounding surface for the rim, and one intermediate the other elements for securing the material in place during the operation of pressing.

In the accompanying drawings, Figure 1 is a front elevation of our machine. Fig. 2 is a perspective view of member 3. Fig. 3 is a perspective view of member 2. Fig. 4 is a perspective view of member 1. Fig. 5 is a vertical section, enlarged, on line 5 5 of Fig. 1, except that the reciprocating parts have been depressed, so that member 2 has come into engagement with the felt upon member 1; and Fig. 6 is a similar view, except that the reciprocating parts are shown in the position when the operation is completed.

Similar numerals refer to similar parts throughout the several views.

In the apparatus shown in the drawings the member 1 is stationary and supported upon the table 12 by any suitable means. This member 1 is provided with the recess 4 for the crown and the marginal surface 5 for the rim of the hat. Said rim-surface 5 is raised above the surrounding surface of the member. Upon this surrounding depressed surface are provided elongated recesses or

slots 6, there being two pairs, one of each disposed diametrically opposite the other.

The member 3 in the apparatus shown is adapted to reciprocate vertically, being supported by the rods 18, adjustably secured by the nuts 19 to the yoke 15, said yoke 15 being supported by rods 9; the adjustment of yoke 15 upon rods 9 being secured by the nuts 11. The member 3 is provided with the crown projection 8, adapted to coöperate with the crown-recess 4 of member 1 and having a surrounding surface 14, (see Fig. 5,) adapted to conform to and coöperate with the surface 5 of member 1.

The intermediate member 2 is supported on the rods 16, which are secured to the frame 10, which is bolted to the yoke 15. Member 2 has a limited free movement upon said rods 16. The compression-springs 20 surround the rods 16 and have operative engagement between frame 10 and member 2 for the purpose hereinafter described. This member 2 is ring-shaped, and its inner margin is adapted to fit the outer margin of the rim-surface 5 of member 1, so that said member 2 will superimpose the depressed surrounding surface of member 1. Upon the under coöperating surface of member 2 are provided ridges or projections 7, similarly disposed and adapted to coöperate with the recesses or slots 6 of member 1 for the purpose hereinafter described. The reciprocation of the rods 9 and frame 10 and the yoke 15 and the consequent movement of members 2 and 3 is accomplished by the operation of the pedal or lever 22, which is connected through link 23 to cross-piece 24, which is secured to the lower extension of rods 9, as shown in Fig. 1.

The operation of our device is as follows: By the operation of the lever or pedal 22 in one direction the yoke 15 is raised, carrying with it the members 2 and 3, member 2 being raised several inches above the surface of member 1. The felt 17 or other material to be operated upon is placed over member 1. The yoke 15 then being lowered, member 2 first engages the felt against member 1, as shown in Fig. 5, the coöperating recesses and projections 6 and 7 securing the felt firmly

at the said four points of coöperation, and as the yoke 15 continues to descend the springs 20 increase their compression to correspondingly increase efficiency of the recess-and-projection engagement of the felt until the member 3 has reached the limit of its downward movement, as shown in Fig. 6, to form crown and rim of the hat. The purpose of the recess-and-projection engagement of the material at four equal distant points is to hold the material firmly and evenly in a manner similar to that in which the material was formerly held at four points by the hands of two operators, so that such portion as must give to the pressure may be given or yielded in the process of pressing. This recess-and-projection engagement is automatic, and while it permits such yielding of the material as is necessary to be yielded between said points of coöperating engagement the said engagement is more efficient and precise than that secured by hand and affords a greater economy of material used. It also saves the time of the operators, and a consequent greater efficiency in production of the machine. The said members or elements are heated in the usual manner for drying and setting the material while under pressure.

What we claim is—

- 30 1. In an apparatus for pressing hats the combination of coöperating elements for crown and rim and a vertically-movable spring-compressed member surrounding one of the coöperating elements and having recess-and-projection engagement with the other coöperating element as means for securing the material to be pressed at evenly-disposed disconnected points prior to and during said pressing, substantially as described.
- 35 2. In an apparatus for pressing hats the combination of coöperating elements for crown and rim and a vertically-movable spring-compressed member surrounding one of the coöperating elements and having recess-and-projection engagement with the other coöperating element as means for securing the material to be pressed at evenly-disposed disconnected points prior to and during said pressing with a constantly-increasing efficiency during the operation, substantially as described.
- 40 3. In an apparatus for pressing hats the combination of coöperating crown and rim forming elements and a vertically-movable spring-compressed member intermediate said two coöperating elements adapted to surround one of said elements and having recess-and-projection engagement with the other said element as means for securing the material at two pairs of oppositely-disposed points prior to and during the operation of pressing, substantially as described.
- 45 4. In a hat-pressing machine the combination of coöperating crown and rim forming elements, an intermediate member adapted to surround one of said elements and having recess-and-projection engagement with the

other said element at evenly-disposed but disconnected points around the margin of the rim-surface and means for operating said elements so that the material to be operated upon is secured by said recess-and-projection engagement prior to and during the operation of pressing, substantially as described.

5. In a hat-pressing machine the combination of coöperating crown and rim forming elements, means for causing their coöperation and a vertically-movable spring-compressed intermediate member adapted to surround one element and to have recess-and-projection engagement with the other said element as means for automatically securing the material to be operated upon at a plurality of disconnected points around its margin prior to and during the coöperation of the crown and rim forming elements, substantially as described.

6. In a hat-pressing machine the combination of coöperating crown and rim forming elements, means for causing their coöperation and a vertically-movable spring-compressed intermediate member adapted to surround one element and to have recess-and-projection engagement with the other said element as means for automatically securing the material to be operated upon at a plurality of disconnected points around its margin prior to and during the coöperation of the crown and rim forming elements, with a constantly-increasing efficiency during the operation substantially as described.

7. In an apparatus for pressing hats the combination of a member recessed for the crown with a surrounding rim-surface, a second member having a coöperating projection conforming with said crown-recess and a coöperating rim-surface, means for causing the reciprocation of one member to and from the other and means for automatically securing the material to be operated upon at evenly-disposed disconnected points about its margin prior to and during the operation of pressing, substantially as described.

8. In an apparatus for pressing hats the combination of two coöperating crown and rim forming elements one provided with a recess for the crown and a surrounding surface for the rim with evenly-disposed disconnected slots around the margin of the rim, the other provided with coöperating crown projection and rim-surface and means for reciprocating one member to and from the other and an intermediate member adapted to surround the rim-surface of the first member having projections corresponding with and adapted to coöperate with the slots in the first member and means for reciprocating said intermediate member to and from said first member, substantially as and for the purpose described.

9. In an apparatus for pressing hats the combination of two coöperating crown and rim forming elements one provided with a recess for the crown and a surrounding surface for the rim with evenly-disposed disconnected

slots around the margin of the rim, the other provided with coöperating crown projection and rim-surface and means for reciprocating one member to and from the other and an intermediate member adapted to surround the rim-surface of the first member having projections corresponding with and adapted to coöperate with the slots in the first member and means for reciprocating said intermediate member to and from said first member with constantly-increasing spring-exerted pressure during the operation of forming, substantially as described.

10. In an apparatus for pressing hats the combination of two coöperating crown and rim forming elements, one element provided with evenly-disposed disconnected slots outside the margin of the rim-surface, and a reciprocating intermediate spring-compressed member having projections corresponding with said slots and adapted to coöperate there-

with for securing the material to be operated upon, substantially as described.

11. In an apparatus for pressing hats the combination of two coöperating crown and rim forming elements, one element provided with evenly-disposed disconnected slots outside the margin of the rim-surface, and a reciprocating intermediate spring-compressed member having projections corresponding with said slots and adapted to coöperate therewith for securing the material to be operated upon, the spring compressing means being so arranged as to secure an efficiency of engagement of the material increasing during the operation, substantially as described.
